UNITED STATES PATENT OFFICE

MINNIE E. NOBLE, OF BERKELEY, CALIFORNIA

DESIGN FOR A BATHER'S SANDAL

Application filed October 12, 1931. Serial No. 41,363. Term of patent 3½ years.

To all whom it may concern:

Be it known that I, MINNIE E. NOBLE, a citizen of the United States, residing at Berkeley, in the county of Alameda and State of California, have invented a new, ornamental, and original Design for a Bather's Sandal, of which the following is a specification, reference being had to the accompanying one sheet of drawings, forming part thereof.

I claim:

The ornamental design for a bather's sandal as shown.

MINNIE E. NOBLE.
